UNITED STATES PATENT OFFICE.

FRANK J. BECKER, OF HAMILTON, OHIO.

MOLDER'S FLASK.

1,072,811.

Specification of Letters Patent.

Patented Sept. 9, 1913.

Application filed August 24, 1912. Serial No. 716,889.

To all whom it may concern:

Be it known that I, FRANK J. BECKER, a citizen of the United States, residing at Hamilton, Ohio, have invented a new and 5 useful Improvement in Molders' Flasks, of which the following is a specification.

My invention relates to molders' flasks of the class adapted to the use of molding machines or for other suitable purposes, and 10 the objects of my improvement are to provide the flask with a telescoping member and with parallel lever connections for moving and maintaining said member in predetermined positions of adjustment in relation 15 to the flask; to provide means for adjusting the flasks to different depths for adapting them to patterns of different thicknesses; to provide means for using the same bottom boards for flasks of different sizes, and to 20 provide simple and durable construction and assemblage of the various parts for securing facility of operation and efficiency of action. These objects may be attained in the following described manner as illustrated in the accompanying drawings, in 25 which:—

Figure 1 is an isometrical view of one member of a molder's flask embodying my improvement, and Fig. 2 a transverse vertical section on the line *a—a* of Fig. 1 with 30 parts broken away and supported upon the other member of the flask.

In the drawings, 1 represents the cope frame of a molder's flask, 2 the drag frame, 35 3 the flask pin and 4 the latch lock, all being constructed and arranged in the ordinary manner. An extension frame 5 consisting of thin metal is slidably mounted within the drag frame. Similar brackets 40 6 are removably secured to the flanged edge 7 and on opposite sides of the frame 5 by means of screws 8. Said brackets are each formed with a plurality of lugs 9 and with a lip 11 in frictional engagement with the 45 corresponding metal plate 12 which is secured thereunder on the outside of the frame 2. A hand lever 13 and a coöperating lever 14 pivotally secured thereto at 15 are fulcrumed at 16 and 17 on one side of 50 the frame 2 and engage at their extremities with corresponding lugs 9 on the adjacent brackets 6 as shown on one side in Fig. 2 and similar levers (not shown) are also connected in like manner to the opposite side 55 of said frame and to similar lugs. Said le-

vers serve to move the frame 5 in an outward direction a predetermined distance and in parallel relation to the frame 2 where it is maintained by the frictional engagement of the lips 11 with the plates 12. The 60 normal depth of the flask may be adjusted to suit different patterns by the loosening of brackets 6 by means of screws 8 for the engagement of the hand levers with the corresponding different lugs 9 on brackets 6. 65

In operation, the drag frame may be placed upon a follow board or upon a match supporting the pattern shown in dotted lines in Fig. 2, and after being extended by means of the hand levers and filled with 70 sand, the bottom board 18 may be placed thereon in the usual manner. The pressure of the molding machine exerted on the bottom board overcomes the friction of the lugs 11 on plates 12 and telescopes the extension frame within the drag frame and 75 properly compresses the sand therein. After the flask is inverted to rest upon the bottom board the match may be removed and the cope frame adjusted in its place. 80 After being filled the usual top board may be placed on the cope frame and forced therein by the machine in the usual manner for compressing its contents. The top board may then be removed to be used repeatedly on the successive molds. The bottom board, however, serves to support the mold on the floor and being of greater area 85 more effectually protects the bottom of the mold. 90

In the use of the ordinary drag frame with a molding machine the bottom boards as well as the top boards are telescoped therein and must correspond in size with that of the flask. For each change in the 95 size of the flask one top board and a large quantity of corresponding bottom boards must be provided. With applicant's device the same bottom boards will serve for flasks of different sizes which effects a saving in 100 the expense required for large numbers of bottom boards for each flask and the labor of supplying and removing them when the flasks are changed.

Having fully described my improvement, 105 what I claim as my invention and desire to secure by Letters Patent of the United States is:—

1. A molder's flask comprising two frames extensibly and frictionally connected to 110

gether, and parallel lever connections for moving them in predetermined extensible relation.

2. In a molder's flask, the combination of a frame, a vertically extensible member frictionally engaging therewith, and adjustable parallel lever connections for moving said member in relation to the frame.

3. In a molder's flask, a drag frame, an auxiliary frame telescoped therein, parallel lever connections fulcrumed on the drag frame and adjustably connected to the auxiliary frame for moving it different predetermined distances and in parallel relation

to the drag frame and frictional connections between the frames for maintaining them in relative adjusted positions.

4. A molder's flask comprising a frame consisting of telescoping members, frictionally connected together and parallel lever movements adjustably connected thereto for relatively moving the frames through different ranges of adjustments.

FRANK J. BECKER.
